UNITED STATES PATENT OFFICE.

PAUL ROWALD, OF HANOVER, GERMANY.

HOLLOW BRICK FOR LEVEL FLOORS AND CEILINGS, &c.

SPECIFICATION forming part of Letters Patent No. 633,044, dated September 12, 1899.

Application filed October 31, 1898. Serial No. 695,057. (No model.)

To all whom it may concern:

Be it known that I, PAUL ROWALD, architect, a citizen of Germany, residing at Hanover, in the Province of Hanover, Kingdom of 5 Prussia, Germany, have invented certain new and useful Improvements in Hollow Bricks for Level Floors and Ceilings, &c.; and I do hereby declare the following to be a full, clear, and exact description of the invention, such 10 as will enable others skilled in the art to which it appertains to make and use the same.

For the construction of fireproof ceilings and floors various designs have been used in particular for covering the open space between the different joists or T-irons supporting the floors. Principally wedge-shaped hollow bricks have been employed for that purpose, the bricks forming part of an arch. Also other shapes of hollow bricks have been 20 used for the same purpose with more or less success. But the laying of all these bricks requires expert masons, and besides their weight is quite a drawback in shipping and in calling for heavier joists. In my invention I avoid almost all side pressure which arches will exert.

My bricks, which I call "omega" bricks, are easily laid, and their weight is so much less than that of other shapes that considerable 30 lighter joists may be employed with safety. My omega bricks may also be used for the construction of light partition-walls, fireproof supports for staircases, &c.

I mold my bricks in such a manner that 35 they contain one or more hollow spaces, but have found that those with two spaces and a rib in the center are the most practicable. The two sides are curved in an ogee form, while the top and bottom are flat and provided with grooves, or they are roughed in some other way in order to make the coating on top or bottom adhere better to them.

In the accompanying drawings, Figure 1 represents a cross-section of an omega brick with one hollow space *a*, and Fig. 2 the same with two hollow spaces *a* and rib *b*. Fig. 3 is a perspective view and shows how the omega bricks are laid in bond between the joists, Fig. 4 how they are placed to make a staircase fireproof, and Fig. 5 how they are used for making partition-walls. Fig. 6 represents an upright omega brick for filling up the en-

tire space between the flanges of the T-irons or where heavier weights are to be supported. *c* and *d* are the roughed top and bottom, and *e* and *f* the two curved ogee sides, which may be 55 symmetrically or parallelly formed, the latter shown by Fig. 7 and applicable to all other forms.

When laying omega bricks between two 60 joists a temporary ceiling is put up and a full-length brick is embedded into mortar upon the lower flange of the T-iron, and then follow other bricks, until the line to the next joist is completed. The next line is commenced with 65 a half of a brick, and then follows a whole brick, and so on until that line is also completed, when the following line is again commenced with a whole brick in order to obtain broken joints all along the entire length of the joists. 70 The joints between bricks are filled out with a thin layer of cement mortar in order to secure a closer fit and to give more stability to the entire structure. Each of these omega bricks is provided with a concave and a corresponding convex face of the ogee form, either symmetrical or parallel, and when placing them in line from joist to joist in one line 75 the symmetrical ones are placed bottom *d* down, and in the next bottom up, and so on, 80 alternately, as appears from drawings, Figs. 3, 4, 5, and 6, but with the parallel ones, Fig. 7, no alternations are required. When the cement is sufficiently hardened, the temporary ceiling is removed and a very strong flat fire- 85 proof ceiling is attained. Fireproof staircase-casings and partition-walls are constructed in a similar manner, as indicated by Figs. 4 and 5.

I claim—

Omega bricks shaped in such a manner that the two opposite upper and lower sides are made conveniently flat and roughed in some ordinary way, whereas the other two sides have an ogee shape, symmetrical or parallel, so that they fit exactly one unto the other thus forming tight joints, all substantially as described.

In witness whereof I have hereunto set my hand in presence of two witnesses.

PAUL ROWALD.
